UNITED STATES PATENT OFFICE.

CHARLES HALLETT, OF CHICAGO, ILLINOIS, ASSIGNOR TO FRANCIS CARL HALLETT, OF RIVER HEAD, NEW YORK.

SEPARATOR.

SPECIFICATION forming part of Letters Patent No. 401,556, dated April 16, 1889.

Application filed January 15, 1889. Serial No. 296,425. (No model.)

To all whom it may concern:

Be it known that I, CHARLES HALLETT, a citizen of the United States, residing at Chicago, in the county of Cook and State of Illinois, have invented certain new and useful Improvements in Steam-Separators, of which the following is a full and exact description.

My invention relates to that class of "steam-separators," so called, placed within a steam-generating boiler above the water-line therein—that is to say, above the surface of the water contained in said boiler—while steam is being generated therein, and in such position that such steam in passing from said boiler through the steam-outlet thereof for use in any manner or in any place wherein a "dry steam," so called, is preferable to wet steam must necessarily pass through said separator.

My invention may be applied to an ordinary horizontal tubular boiler or to the dome thereof, and to an ordinary vertical tubular boiler; but in the drawings accompanying and forming a part of this specification I have illustrated my invention as applied to an upright radial tube-boiler.

Where steam is taken from boilers for use in obtaining motion by passing the same through a motor of any kind, it is very desirable that such steam shall enter and pass through said motor in as dry a form as possible, and it has also been found advantageous to "superheat" said steam, as it is termed, before it so passes to and through said motor. It is well known, too, that where steam-generating boilers are used for certain purposes, as in generating steam for actuating motors propelling small boats, it is desirable that said steam-generating boiler be so constructed that the center of gravity thereof shall be as low as possible therein, and this is particularly essential where said boiler is a vertical boiler; and for this reason it is highly important to so design the boiler that there shall be as small an amount of metal therein above the water-line thereof as practicable, and that there be very little steam-space above the water contained in said boiler and between the upper end thereof and the surface of the water.

The object of my invention is to obtain a steam-separator which may be used alone and independently of all other steam-separators

for all the hereinabove-named purposes, and for others wherein a dry steam is desired, and which may, when required, be used in connection with and in addition to steam-separators of the kind heretofore made.

In the drawings, Figure 1 is an elevation of my invention designed to work as a steam-separator and superheater, and applied to a boiler which I have found to be peculiarly well adapted to be placed in a small steam-propelled boat or launch for generating steam actuating the motor of said boat. Fig. 2 is a front elevation of another manner of applying my invention to an upright boiler. Fig. 65 3 is the side elevation thereof. Fig. 4 is a side elevation of my invention applied to an upright boiler in combination with a separator heretofore made and applied to said boiler.

As hereinbefore stated, I have illustrated my invention as applied to an upright boiler consisting of a vertical cylinder having radial tubes thereon extending outward from said cylinder through the furnace of said boiler above the fire-pot thereof to or nearly to the outer casing of said furnace; but it is evident that my invention can be applied to an upright tubular boiler or to a horizontal tubular boiler in substantially the same manner as it is applied to the boiler herein illustrated, the radiating arms of the herein-illustrated boiler forming no part of my invention.

The device embodying my invention as applied to a boiler of the kind illustrated in Fig. 1 is constructed as follows: A is a boiler having radial tubes *a* thereon. *a'* is the water-line of the boiler, and *a''* is the upper head or end thereof. B' is the chimney of the furnace of the boiler. C is an iron pipe, cylinder, or tube having a closed end, C', and secured at the other end to head *a''* of boiler A. Cylinder C forms an extension of the boiler and is hereinafter referred to as "tubular extension," C. This tubular extension C may be constructed of the same material as boiler A is constructed of, and has heretofore been attached to said boiler A by securing a cast flange, D, to the head of the boiler and fastening said tubular extension into said flange. E is the steam-outlet pipe. This steam-outlet pipe E passes through the casting of the furnace in this form of construc-

tion, through the furnace of the boiler above the fire-pot thereof, and into the boiler A above the water-line of said boiler. F is an extension of steam-outlet pipe E, and is connected thereto by an ordinary steam-pipe joint or coupling. Pipe F extends inward toward the center of the boiler A and underneath tubular extension C, from whence it extends upward and into said tubular extension. f f are perforations in tube or pipe F in that portion of said pipe F contained within tubular extension C. G G is a wire-woven cloth wound around pipe F over that portion thereof within which perforations f f are made. I have found it desirable to use metal cloth having a mesh not exceeding one-sixteenth of an inch in the open part thereof, and to wind or wrap said cloth twice or slightly more around pipe F. It is evident, however, that the number of times such cloth is wrapped around such pipe F is or may be controlled to a certain extent by the size of holes f in pipe F, as the purpose of cloth G used, as described, and in combination with the perforated pipe F, is to permit steam contained in tubular extension C of said boiler A to pass therefrom into pipe F, and from thence to steam-outlet E as such steam is required for use, and to prevent particles of water passing from said tubular extension C along with said steam and into said pipe F. It will be observed that in this construction steam-outlet E and the contents thereof are subjected to intense heat from the furnace B of said boiler in that portion of said steam-outlet E located between the shell or case of boiler A and shell or casing H of the furnace B, and the steam passing therefrom is thereby, to a certain extent, superheated.

In the form of boiler to which my invention is illustrated as attached in Figs. 2 and 3, wherein it is desired to so construct such boiler that man-hole I may be placed upon the top of the boiler, through which entrance may be had to the interior thereof, I have illustrated the device embodying my invention or a part thereof in a slightly-different form of construction. In this form of construction the water-line, it will be observed, must be relatively somewhat lower in reference to the upper end, a'', thereof than in the boiler illustrated in Fig. 1.

In Figs. 2 and 3 E is the steam-outlet pipe. F F are pipes closed at the outer ends thereof, respectively, and having perforations f f f therein and secured to steam-outlet pipe E at the inner ends thereof. In order that steam-outlet pipe E may be removed from the boiler when desired, I have placed an ordinary steam-coupling joint, e, in steam-outlet pipe F in this form of construction, and when access is desired to the interior of said boiler the cover of man-hole I must be removed and that portion of steam-outlet pipe E to which pipes F are secured detached at coupling-joint e and removed from said boiler. G is wire-cloth wound around perforated pipe F

in the same manner as hereinbefore described.

In the boiler constructed as in Fig. 4, 70 wherein the steam is taken from the top thereof and a separator of the ordinary construction used in connection therewith, I have illustrated my device, or a portion thereof, applied to said boiler and working in combination with said separator in the following manner: J is the separator heretofore used on said boiler. K is a diaphragm in the boiler above the water-line thereof and having a hole therein, over which said separator 80 J is placed. k k are drip-pipes extending through diaphragm K downward and below the water-level in boiler A. F is a pipe having perforations f f therein, as hereinbefore described, secured to separator J and to diaphragm K, and extending downward from said diaphragm into the steam-space between said diaphragm and the water-level of the boiler. The lower end of perforated pipe F is closed, and around the perforations f f is wound metal cloth, G, as hereinabove described.

The operation of my device is as follows: When steam is generated in the boiler, it ascends therein and into the steam-space of 95 said boiler, and as the pressure of the steam in such steam-space becomes sufficient it forces its way through the perforations in metal cloth G into pipe F, from which said pipe F it is taken for use in the ordinary 100 manner. In practice I have found the steam issuing from the boiler supplied with my separator to be extremely dry, and no other separator to be required; but I have made use of my invention in the manner herein 105 described, in combination with other separators, thereby improving the character of the steam obtained from said boilers.

Having thus described my invention, what I claim, and desire to secure by Letters Patent, 110 is—

1. In a steam-separator, the combination of a pipe having one end thereof closed, perforations in the pipe, and metal cloth wound one or more times around the perforated pipe 115 in close contact therewith, whereby steam entering the perforated pipe must pass through the meshes of the cloth, all substantially as described.

2. In a separator for steam-generating boilers, a pipe having perforations therein placed in the steam collector or dome of said boiler formed by a tubular extension thereon of less diameter than said boiler, in combination with a metal wrapping having small perforations therein wound around the perforations in said pipe, and a steam-outlet pipe passing from said dome or collector through the furnace of said boiler, whereby steam generated in said boiler passing through said separator 125 in leaving said boiler by said steam-outlet pipe shall pass through the furnace of said boiler above the fire-box thereof, all substantially as described.

3. In a steam-separator, a pipe having perforations therein placed within a steam-generating boiler above the water-line thereof, in combination with metal cloth wrapped around
5 the pipe and over the perforations therein, and a steam-outlet pipe passing from and a continuation of the perforated pipe and ex-

tending through the furnace surrounding the boiler above the fire-pot therein, all substantially as described.

CHARLES HALLETT.
